UNITED STATES PATENT OFFICE.

JULIUS EMDEN, OF HAMBURG, GERMANY.

SAFETY-VAN FOR RAILWAY-TRAINS.

SPECIFICATION forming part of Letters Patent No. 639,367, dated December 19, 1899.

Application filed January 3, 1899. Serial No. 701,020. (No model.)

To all whom it may concern:

Be it known that I, JULIUS EMDEN, a citizen of the Empire of Germany, residing at Hamburg, Germany, have invented certain new and useful Improvements in Safety-Vans for Railway-Trains, of which the following is a specification.

This invention relates to safety-vans for railway-trains, the object being to provide a van, truck, or wagon to be inserted between the engine and the first wagon or car of the train for the purpose of avoiding running off the rails as much as possible and deadening the jerks produced on the engine by collision or braking; and it consists in the novel construction, combination, and arrangement of parts hereinafter fully described, and specifically pointed out in the appended claims.

In order that this my invention may be more readily understood and carried into practical effect, reference is hereby made to the accompanying illustrative drawings, in which—

Figure 1 shows the head portion of a railway-train with the improved safety-van constructed in accordance with my invention. Fig. 2 is a plan view of the safety-van shown in Fig. 1. Fig. 3 is a sectional end view on line $x x$ of Fig. 1. Fig. 4 is a vertical section on line $y y$ of Fig. 1. Fig. 5 is a perspective view of the safety-van, and Fig. 6 is a similar view of the specially-constructed engine.

In the drawings like letters refer to like parts throughout all the figures.

The new or improved safety van, truck, or wagon c is embodied in any suitable strong and heavy construction, so as to have sufficient weight and resistance to withstand and take up the jerks produced on the engine by collisions or sudden braking.

From the lower fore part of the safety van, truck, or wagon extend horizontally-projecting beams or girders $a a$, running along the sides of the engine-frame or extending into loops or openings provided in the bottom of the engine, correspondingly constructed or modified, whereby the latter will be prevented from running off the rails, as might otherwise occur by collisions. The central and upper part of the safety van, truck, or wagon is provided with similar beams or girders $b b$, suitably connected with the frame of said safety-

van and extending through loops d , arranged on posts or supports d' , secured on the engine-frame. Said beams or girders $b b$ will form a kind of roofing over the engine to prevent the latter from being lifted over the rails.

Under the side beams or girders $a a$ are cross-beams e , suitably secured to the engine-frame, for the purpose of preventing the engine from being lifted by engaging said beams or girders $a a$.

The various beams or girders are horizontally arranged, so that the engine might freely move into and out of engagement with said beams or girders to be easily and readily coupled and uncoupled and to leave sufficient space for storing coal and the like.

On the rear side of the safety van, truck, or wagon, which is not provided with the usual buffers, I have disposed a suitable cushion s , and the adjacent side of the next wagon, also unprovided with buffers, has a similar cushion s , said cushions serving as a substitute for the buffers to take up the jerks produced by collisions or sudden braking.

I wish it to be understood that I do not restrict myself to the precise construction and relative arrangement of parts shown and described so long as the peculiar features of the invention be retained.

Having fully described my invention, what I claim, and desire to secure by Letters Patent, is—

1. A van or car adapted to be coupled up in a train intermediate the locomotive and the adjacent car, comprising a framework mounted upon supporting-wheels to adapt it to run upon the rails, and longitudinally-arranged beams or girders projecting forwardly beyond the framework, said beams being arranged toward each side of the framework at the top and bottom thereof, the upper beams being adapted to extend over the locomotive and engage with a fixed part thereof, to prevent the locomotive rising vertically off of the rails, and the lower beams being adapted to extend along each side of the locomotive to prevent lateral movement thereof.

2. A van or car adapted to be coupled up in a train intermediate the locomotive and the adjacent car, comprising a framework mounted upon supporting-wheels to adapt it to run upon the rails, and longitudinally-ar-

ranged beams or girders projecting forwardly beyond the framework, said beams being arranged toward each side of the framework at the top and bottom thereof, the upper beams being adapted to extend over the locomotive and engage with a fixed part thereof to prevent the locomotive rising vertically off of the rails, and the lower beams being adapt-

ed to extend along each side of the locomotive to prevent lateral movement thereof, and a buffer arranged at the rear end of the van.

JULIUS EMDEN.
